His ATTORNEY.

Patented Jan. 17, 1928.

UNITED STATES PATENT OFFICE.

ORIN E. MARVEL, OF DAYTON, OHIO, ASSIGNOR TO THE DAY-FAN ELECTRIC COMPANY, OF DAYTON, OHIO, A CORPORATION OF OHIO.

ADJUSTABLE-CORE TRANSFORMER.

Application filed June 5, 1923. Serial No. 843,543.

This invention relates to a device for the transfer of high frequency electrical energy from one circuit to another as from the plate circuit of a vacuum tube to the grid, or control circuit of the following tube.

It is one of the principal objects of my invention to provide a transformer with variable inductance and impedance, so that the transformer will transfer this high frequency energy at its maximum efficiency over a band of frequencies. The band of frequencies that the transformer will cover is determined by the number of turns of wire of the primary and secondary windings and the iron core. The efficiency of the transfer of energy of the transformer with a given number of turns in the primary and secondary winding and iron core for a given band of frequencies, will depend upon the amount of the iron core that links in the path of the magnetic flux set up by the current flowing through the primary and secondary windings of the transformer.

It is another object of my invention to provide a means of actuating the movable iron core in such a manner that it will change the inductance and impedance of the transformer over the band of frequencies for which the transformer may be designed.

It is another purpose of my invention to provide a means of keeping the potential of the iron core at zero with respect to the negative or common side of the electrical circuits.

It is still another object of my invention to provide a means of accelerating the dissipation of the electrical charge of the capacity of the primary and secondary windings, upon the reversal of the cycle of the electrical energy which is being transferred from one circuit to another.

It is a further object of my invention to provide a method of winding the primary and secondary coils so that they will have a small distributed capacity between their ends and the proper amount of capacity between the primary and secondary windings for an efficient transfer of high frequency energy over a given band of frequencies.

In the accompanying drawings, Figure 1 is a longitudinal, sectional view of my transformer, taken on the line 1—1 of Figure 3. Figure 2 is a side elevational view of the same, partly in section, illustrating diagrammatically the method of winding the pri-

mary and secondary wires. Figure 3 is a cross sectional view taken through the transformer on the line 3—3 of Figure 1. And Fig. 4 is a schematic diagram illustrating one application of my transformer.

Throughout the specification and drawings, similar reference characters denote corresponding parts.

In the accompanying drawings illustrating one form of embodiment of my invention, the numeral 1 designates an elongated cylindrical casing made of non-conductive electrical material such as bakelite or special radio fiber.

Formed on the rear end of the casing 1 is an annular flange 2, and on its middle portion there is an integral annular flange 3. Between these flanges the casing 1 forms a bobbin to receive a primary winding 4 and a secondary winding 5. The primary winding 4 is connected between binding posts 6 and 7 on the flanges 2 and 3 respectively, while the secondary winding is connected between binding posts 8 and 9 on the same flanges. (See Figure 2.) These windings are layer wound on the casing 1, without doubling back on any turn. This method of winding gives a small distributed capacity and the proper amount of capacity between the primary and secondary windings for an efficient transfer of high frequency energy over a given band of frequencies.

Longitudinally movable into and out of the wound part of the casing 1, is a non-magnetic split sleeve 10 preferably of copper whose interior is lined with suitable insulating material 11 which surrounds a laminated core 12 made up of very thin strips of high frequency iron. (See Figure 3.)

Suitably secured to the front end of the sleeve 10, for the purpose of moving it longitudinally within the casing 1, is a rod 13 which carries on its front end a knurled knob 14. This rod is calibrated for desired wave lengths by having provided on its rear portion graduations 15 corresponding to those wave lengths. A desired wave length may be readily selected by moving the rod to a position wherein a graduation 15 designating that wave length is in alignment with the front end of the casing 1. The rod 13 thus provides a selective and convenient means for changing the position of the iron core containing-sleeve 10 within the wound part of the casing 1 to change the inductance

and impedance of the transformer over the band of frequencies for which it is designed, although other suitable means may be employed for this purpose if desired.

5 The middle of flange 3 is provided with a radial hole which extends through the casing 1, to receive a screw 16 whose inner portion is hollow to contain a helical spring 17 which presses a carbon brush 18 into engagement 10 with the iron core containing-sleeve 10. A wire 19 connects the screw 16 with the secondary wire 5 so that the brush 18 will ground the sleeve 10, thereby tending to maintain the sleeve and secondary filament 15 at ground potential when the transformer is used for radio purposes. The purpose of this is to accelerate the dissipation of the electrical charge of the capacity of the primary and secondary windings, upon the reversal of the cycle of the electrical energy being transferred from one circuit to another.

20 Adapted to be slipped over the flanges 2 and 3, behind a front flange 20 on the casing 1, is a cap or shell 21 to cover the primary and secondary windings. This cap may be readily applied and removed.

25 As already stated the present invention relates primarily to the transfer of high frequency electrical energy from one circuit to another, and is particularly applicable for use in a radio receiver, or like apparatus, employing vacuum tubes for amplifying high frequency energy oscillations. In such apparatus high frequency energy oscillations are transferred from the plate or output circuit of one vacuum tube to the grid or input circuit of the next succeeding vacuum tube, said circuits being coupled in energy transmitting relation with one another. 30 Such coupling may be effected by means of the transformer herein described, the primary winding 4 being connected in the plate circuit of the first vacuum tube and the secondary winding 5 being connected in the 35 grid circuit of the second vacuum tube.

40 The connection of the transformer in such energy transferring relationship between the plate and grid circuits as just described is illustrated in the schematic diagram of Fig. 4 which shows the conventional and well known arrangement of circuits for connecting one vacuum tube 30 with the next succeeding vacuum tube 31. In this arrangement, the plate circuit 32 of the first vacuum tube 30 is coupled with the input or grid circuit 33 of the second vacuum tube 31 in the usual way by a transformer, the primary winding 4 of which is in the plate circuit 32 and the secondary winding 5 of which is in 45 the grid circuit 33, which latter circuit, it will be observed, extends from the grid of the tube 31 through the secondary winding 5 to the filament of the tube 31. That portion of the grid circuit 33 which is between the 50 secondary 5 and the filament of the tube 31

is, because of its interrelation with other circuits not herein illustrated, commonly said to be on the negative or common side of the circuit. The sleeve 10 of the transformer is connected with or grounded to that terminal 70 of the secondary winding 5 which is connected to the negative or common side of the circuit and hence the sleeve is at the same potential as this side of the circuit.

75 In the operation of an apparatus as described, when it is desired to transmit oscillations of a given frequency or wave length from the plate circuit 32 to the grid circuit 33, the iron core 12 of the transformer is moved to the position which will insure the 80 most effective transfer of energy from the primary winding 4 to the secondary winding 5, the proper position for the core being indicated by the calibrations on the stem 13. When it is desired to transmit oscillations of 85 a different frequency the position of the core 12 is changed in accordance with the calibrations on the stem 13 so as to again obtain the most effective transfer of the energy. By 90 adjusting the iron core in this manner the amount of iron that links with the magnetic fields of the primary and secondary windings is changed from which it follows that the inductance and impedance of these windings also change with the position of the iron core 95 within the windings. From the foregoing, it will be apparent that the movement of the core 12 within the windings results not only in a variation of the impedances of the windings but also in a simultaneous variation of the impedances of the plate and grid 100 circuits in which they are connected, and hence the movement of the iron core constitutes a simple means for tuning these circuits for the most effective and efficient transfer of energy between them. The purpose of splitting the copper sleeve 10 as shown in the drawings is to prevent the formation of undesirable eddy currents which tend to neutralize the action of the windings and to 105 hinder the proper transfer of energy between the windings. Another advantage of the present invention is that it provides means for effecting sharp tuning of the apparatus in which it is incorporated.

110 Having described my invention, I claim:

1. A transformer comprising a casing, a primary and a secondary winding surrounding the latter, a non-magnetic split sleeve movable in said casing, an iron core within the sleeve, and means for grounding said sleeve.

115 2. A transformer comprising a hollow bobbin formed of insulating material, primary and secondary windings disposed in inductively coupled relationship with one another about said bobbin, and means for manually changing the inductance and impedance of the transformer, said means disposed within said bobbin comprising mag- 120 125

- netic means magnetically coupled with both of said windings, non-magnetic conducting means disposed to have capacity coupling with both of said windings, and means for 5 grounding said non-magnetic means.
3. A transformer comprising a casing, a primary and a secondary winding surrounding the latter, a non-magnetic sleeve movable in said casing, a brush in contact with the 10 sleeve, a housing in said casing for the brush, and a wire connected between said housing and the secondary winding for the purpose specified.
4. A transformer comprising a casing, a primary and a secondary winding surrounding the latter, a non-magnetic sleeve movable in said casing, said casing containing a radial hole, a hollow screw in the latter, a helical spring contained within said screw, 20 a brush also in said screw adapted to be forced into engagement with the sleeve by the spring, and a wire connected between said screw and the secondary winding for the purpose specified.
5. A transformer comprising concentrically disposed primary and secondary windings, a non-magnetic sleeve disposed adjacent said windings and longitudinally movable relative thereto, and conducting means connected between said sleeve and one of said 25 windings, to ground the former.
6. A transformer adapted to receive high frequency oscillations of varying frequencies, comprising a primary winding, a secondary winding inductively coupled with 30 said primary winding and supported in fixed relation thereto, and means for varying the inductive relation of said windings to ac-
- cord with the frequency of the oscillations received, said means including a member of magnetizable material mounted for movement in the magnetic field of said windings, non-magnetic means substantially surrounding said magnetizable member and disposed to have capacity coupling with both of said 40 windings, and provisions for grounding said non-magnetic means.
7. In an apparatus of the character described, a high frequency transformer having a primary winding, a secondary winding 45 disposed in inductively coupled relationship with said primary winding, an iron member movable in the magnetic field of said windings, and means independent of said iron member for accelerating the dissipation of the electrical capacity charge upon the primary and secondary windings 50 upon reversal of cycle of the electrical energy impressed upon the transformer.
8. In an apparatus of the character described, a high frequency transformer adapted to receive high frequency oscillations of varying frequencies, having a primary winding, a secondary winding inductively coupled with said primary winding, and an iron member movable in the magnetic fields 55 of said windings for varying the inductive properties thereof, said windings comprising concentrically disposed coextensive coils each consisting of a single layer of wire 60 whereby to provide small distributed capacity between the ends thereof.

In testimony whereof I have hereunto set my hand this 4th day of June, 1923.

ORIN E. MARVEL.

CERTIFICATE OF CORRECTION.

Patent No. 1,656,381.

Granted January 17, 1928, to

ORIN E. MARVEL.

It is hereby certified that error appears in the printed specification of the above numbered patent requiring correction as follows: Page 2, lines 129 and 130, claim 2, strike out the words "disposed within said bobbin" and insert the same to follow after the word "means" in line 1, page 3, of the same claim; and that the said Letters Patent should be read with this correction therein that the same may conform to the record of the case in the Patent Office.

Signed and sealed this 14th day of February, A. D. 1928.

Seal.

**M. J. Moore,
Acting Commissioner of Patents.**
